UNITED STATES PATENT OFFICE.

REINHARD E. BARTELS, OF NEWTON, MASSACHUSETTS.

BOOT OR SHOE.

1,089,036.

Specification of Letters Patent.

Patented Mar. 3, 1914.

Application filed September 4, 1913. Serial No. 788,100.

To all whom it may concern:

Be it known that I, REINHARD E. BARTELS, a citizen of the United States, and a resident of Newton, in the county of Middlesex and State of Massachusetts, have invented certain new and useful Improvements in Boots or Shoes, of which the following is a specification.

This invention has relation to leather foot-wear, such as boots, shoes and slippers.

Owing to certain natural causes, which it is unnecessary to discuss in detail, the cost of boots and shoes has been gradually increasing, notwithstanding improvements in machines and processes of production. One of the factors of increased cost has been the increasing cost of the upper leather which must be used since no effective substitute has been found which will take the place of leather in shoe making. The use or omission of a small amount of leather varies the cost of the shoe, particularly in shoes of high grade.

The object of the present invention is to effect a material saving in the cost of construction of a given boot or shoe by decreasing the amount of leather used in its manufacture, without detracting from its appearance or wearing qualities, and at the same time to provide a better shoe by eliminating the stretching which permits a shoe to become mis-shapen in the course of a short time.

According to the usual process of manufacture, the upper and the lining, which is usually of relatively light material, are placed upon the last, and attached temporarily to the inner sole, after which the shoe is either welted and stitched or turned stitched or is McKay stitched to secure the outer sole thereto. In the preliminary pulling-over operation, the fringe or loose marginal portions of the upper are overlapped upon the inner sole, and tacks or fastenings are driven therethrough into the inner sole. Then the edge of the leather upper and the welt are sewed to the inner sole by stitches passing through the leather upper, or the sole is sewed on by a McKay machine or a turn machine, the stitches passing through the marginal portion of the leather upper.

According to my invention, I cut the upper so that the edge or margin thereof will

not be pierced by the stitching or welting operation, and so that it will terminate short of the line of the welt stitches or the McKay stitches. In this way, I effect a material saving of the leather. Further, between the lining and the leather I place one or more layers of flexible, substantially non-extensible material, such as heavy drill or canvas, which are secured at their upper edges to the leather by the usual seams which are employed in forming the upper. This layer or layers has a marginal portion which projects materially beyond the bottom margin of the upper leather, so that it can receive the fasteners and the stitches which are used in soling or bottoming the shoe. And then, the margin of the leather is secured by one or more lines of stitches to the non-extensible layer, so that it will be secured in place and hidden by the welt or by the sole according to the character of the shoe. In this way, I do not have to consider the stretch of the leather, and the uppers may therefore be cut from any portion of the skin. Consequently the entire skin may be used to the greatest advantage.

As a direct consequence of my invention, I am able to effect a material saving since I am able to use very thin leather of fine texture which would be otherwise practically impossible to employ because of its limpness and liability to stretch.

On the accompanying drawing,—Figure 1 represents a pump or slipper embodying the invention. Fig. 2 shows the upper thereof before it and the other parts are assembled on the last. Fig. 3 represents a section on the line 3—3 of Fig. 2. Fig. 4 shows the pump or slipper after the upper has been pulled over or lasted and secured to the insole, preparatory to the attachment of the outer sole by a McKay sewing machine. Fig. 5 represents a transverse section through the ball of the completed pump. Fig. 6 represents a longitudinal section through the toe of a shoe embodying the invention. Fig. 7 represents a transverse section through a welt shoe embodying the invention.

By the use of the term "shoe" in the appended claims, I mean to include foot-wear of all kinds,—boots, shoes, pumps, slippers, etc.

It will be understood, of course, that whereas I have shown the invention as embodied in a lady's slipper or pump, the invention may be embodied in any kind of 5 footwear.

On the accompanying drawings,—a shoe is illustrated having the usual inner sole 10.

11 represents the outer sole which, in the shoe illustrated in Figs. 1 to 5, is secured in 10 place by a line of stitches indicated at 12 which pass through both the outer sole and the inner sole. The upper consists of an outer layer 13 of leather which forms the 15 vamp of the shoe. Within the vamp is the usual thin lining 14 which, at its upper edge, is secured to the edge of the vamp in any of the usual ways. Between the lining and the leather vamp there is a layer of flexible non-elastic material, drill, canvas or the 20 like, as indicated at 15. Only one layer may be utilized, or, if desired, I may employ two layers as shown in Figs. 3 and 5. Where the upper is to be employed in a McKay shoe, the leather portion 13 is cut so that its 25 margin will extend a short distance into the space between the inner sole and the outer sole, as shown in Fig. 5, and yet not far enough so as to be penetrated by the line of stitches 12. By reference to Fig. 2, it will 30 be seen that a relatively large marginal area of the layers 15 is exposed to view, this exposed portion indicating the amount of leather which is saved by thus cutting the leather vamp. The exterior margin of the 35 leather vamp is secured to the interior layer or layers 15 by one or more lines of stitches 16. Hence, when the upper is pulled over the last and the intermediate layer 15 is drawn taut about the last and is secured in 40 place, the leather vamp is thereby drawn over the edge of the inner sole and is likewise secured in place. The line of stitches 16 is so located that it is concealed when the shoe is finished, the edge of the upper 45 being likewise concealed.

The upper edge of the reinforce is also secured to the upper edge of the vamp by the line of stitches which secure the lining thereto, as shown at 21 in Fig. 1.

50 It will be observed that the vamp is provided with a toe cap 19 which is connected to the front end thereof by one or more lines of stitches 20 extending across the upper from one side edge to the other. These 55 stitches penetrate the reinforce or intermediate layer so that the toe cap is secured thereto. The line of stitches 16 extends around the curved margin of the toe cap so that the latter is attached to the reinforce 60 around its entire margin or edge. The extremity of the toe cap, as shown in Fig. 6, terminates short of the stitches which connect the upper to the bottom of the sole. Frequently the toe cap is made of enameled 65 leather, and the cracking of the cap, which

is due to the lasting operation, entails considerable expense or loss. This is due to the fact that the leather is flexible and expansible, whereas the enamel is non-expansible, and consequently, when the leather is 70 stretched, cracks are formed where the leather is drawn over the inner sole. By securing the edges of the toe cap to the reinforce, the leather is prevented from stretching, and I thus eliminate the cracking and injuring of the enamel. This is a valuable feature of the invention which may be utilized independently of the other features; that is to say, whether or not the ball and shank portions of the upper be provided 75 with the reinforce, the toe cap may be provided with the reinforce and be stitched thereto along its margins for the purpose of saving the toe cap from cracking.

In Fig. 6, I have shown the invention as 80 embodied in a welt shoe. In this case, the line of stitches 16 is hidden by the welt 17, the edge of the leather vamp terminating just short of the stitches 18 which secure the 85 welt, the upper and the inner sole together. 90

Inasmuch as the reinforcing layer 15 of textile material is secured at its upper and lower edges to the leather vamp, it will be seen that, after the reinforcing layer has been drawn taut and the shoe has been lasted 95 100 and stitched, it takes the pressure exerted by the foot of the wearer and prevents stretching of the leather. Hence, in a shoe embodying the invention, there is little danger of the shoe becoming distorted or mis-shaped 105 after wear. It prevents the bulging of the upper laterally beyond the edges of the sole as frequently happens when the leather is soft and spongy. By the use of the reinforced layer, therefore, it is possible to utilize substantially the entire skin in making the uppers, and there is no necessity for a careful spacing of the patterns on particular 110 portions of the skin as is now the case.

Having thus explained the nature of my 110 said invention and described a way of making and using the same, although without attempting to set forth all of the forms in which it may be made or all of the modes of its use, what I claim is:—

115 1. A shoe having a vamp, a non-elastic reinforce substantially coextensive in area with the vamp but projecting beyond the bottom of the vamp, stitches connecting the upper and lower margins of the vamp to the reinforce, and means for securing the projecting marginal portion of the reinforce to the bottom of the shoe.

120 2. A shoe having the usual inner and outer soles, a leather vamp whose bottom margin is concealed but terminates short of the seam connecting the upper and the inner sole, a non-elastic reinforce substantially coextensive in area with the vamp and whose bottom portion projects beyond the margin 125 130

of the vamp and is secured to the inner sole, and stitches connecting the margin of the vamp to the reinforce.

3. A leather upper for shoes comprising a vamp, a lining, an intermediate reinforce projecting beyond the bottom edge of the vamp, and stitches securing the upper and bottom margins of the vamp to the reinforce, whereby the projecting marginal portion of the reinforce may be pulled over and secured to a sole, and by its connection with the vamp secure the leather vamp in place without unduly stretching the leather vamp.

4. A shoe having a sole, a vamp, a toe cap, a non-elastic reinforce for the toe cap, stitches connecting the reinforce to the sole, and stitches connecting the entire margin of the toe cap to the reinforce independently

of the stitches which secure the reinforce to the sole.

5. A shoe having a leather vamp terminating in a toe cap, the bottom margin of the vamp and toe cap being concealed but terminating short of the seam connecting the upper and the sole, a non-elastic reinforce whose bottom portion projects beyond the margin of the vamp and toe cap and is secured to the sole, and stitches connecting the upper and lower margins of the vamp and toe cap to the reinforce.

In testimony whereof I have affixed my signature, in presence of two witnesses.

REINHARD E. BARTELS.
